Edmund W. Baggott, Brooklyn, N. Y., assignor to
Ideal Novelty & Toy Co., Long Island City, N. Y.,
a corporation of New York

Application November 27, 1944, Serial No. 565,327

5 Claims. (Cl. 41—34)

My invention relates to a new and improved assembled body, and to new and improved structural units for making such assembled body.

The assembled body may be used for making a wall of a hand-bag and for numerous additional purposes.

According to my invention, the assembled body consists of rigid interlocked units which are connected and held assembled in turnable relation by rigid interlocking means to form a mesh structure, so that said units cannot separate from each other, and they can turn relative to each other, in order to provide a flexible assembly. Said units are also connected to each other by a single series of flexible members, which may be wires, cords, tapes or the like, thus eliminating the necessity of using two such series, in which the members of one series are perpendicular to the members of the other series.

Numerous additional objects of my invention are stated in the annexed description and drawings, which illustrate a preferred embodiment thereof. For convenience, it is assumed that the units are assembled to form horizontal rows and vertical rows, each unit being located in a respective vertical row and in a respective horizontal row.

Fig. 1 is a plan view at the outer or exposed face of part of the assembly, showing four units, and parts of units which are adjacent said four units. The units which are illustrated in Fig. 1 are designated as intermediate units, because they are located intermediate the end-units of their respective rows.

Fig. 2 is a plan view of the assembly of Fig. 1, taken at the inner or concealed face of said assembly.

Fig. 3 is a plan view of a single intermediate unit, taken at its outer face.

Fig. 4 is an outer plan view of an end-unit which is used at one end of a horizontal row which is located between the top and bottom horizontal rows.

Fig. 5 is an outer plan view of an end-unit which is located at a corner of the assembly. This end-unit is located in the bottom horizontal row.

Fig. 6 is a section on the line 6—6 of Fig. 3.

Fig. 7 is an outer plan view of an end-unit which is used at the end of a vertical row which is located between the edge vertical rows.

Fig. 8 is an outer plan view of another end-unit which is located in a corner of the assembly, in the bottom horizontal row.

Fig. 9 is an outer plan view of an end-unit 55

which is used at an end of an intermediate horizontal row.

Fig. 10 is an outer plan view of another corner end-unit.

Fig. 11 is an outer plan view of a top end-unit which finishes a respective intermediate vertical row.

Fig. 12 is an outer plan view of another corner end-unit.

Fig. 13 shows the assembly, utilized to form the walls of a hand-bag.

Fig. 14 is a diagrammatic view which shows how the respective connecting members are interlaced with the units.

For convenience, the invention is described with reference to a hand-bag structure B, in which each unit is located in a horizontal row or series, and also in a vertical row or series. Fig. 13 shows a top horizontal edge-row 22, a bottom horizontal edge-row 23, a left vertical edge-row 24, a right vertical edge-row 25, and intermediate rows 26.

Each of the intermediate rows 26 comprises a plurality of intermediate structural units 1.

The top horizontal edge-row 22 comprises a left corner-unit 15, a right corner-unit 14, and additional top-units 16.

The bottom edge-row 23 comprises a left corner-unit 18, a right corner-unit 17, and additional bottom units 19.

The left corner-units 15 and 18 are the top and bottom units of the left vertical edge-row 24, which has additional edge-units 10. The right corner-units 14 and 17 are the top and bottom units of the right vertical edge-row 25, which has additional units 20.

The respective units are made of metal, plastic, or any other material. They are rigid or resilient. If resilient, they are sufficiently rigid to keep them in predetermined normal shape.

Each unit has a face-wall 2. Said face-walls 2 are of square outline in this embodiment. The face-walls 2 of the respective units are identical in area. Each face-wall 2 has a planar outer face.

Each intermediate unit 1 is of general cup shape. It has lugs 4 and 6, and flanges 3 and 5. Figs. 1-12 are to full scale and reference is made thereto for further details. The flanges 3 and 5 are integral at a respective corner of the unit 1.

The intermediate units 1 are identical. The lugs 4 and 6 of each intermediate unit 1 have respective lug-slots 7 and 7a, of rectangular shape. The width of each lug-slot 7 and 7a is less than its length.

The flanges 3 and 5 of each intermediate unit 1 have respective flange-slots 8 and 8a. Respective walls of said flange-slots 8 and 8a have respective recesses 9 and 9a. These recesses 9 and 9a may be omitted. They facilitate the insertion of the connecting members 21.

The free edges of the lugs 4 and 6 and of the flanges 3 and 5 are in the same plane, which is parallel to the plane of the outer surface of the face-wall 2.

Each lug 4, 6 and each flange 3, 5 is of convexo-concave shape. Said lugs and flanges are substantially perpendicular to the face-wall 2 of the respective unit.

Each intermediate unit 1 is interlocked with the next adjacent vertical unit and with the next adjacent horizontal unit by a respective lug and flange. Each lug is located in a respective lug-slot when the units are assembled, thus providing a turnable connection between each pair of adjacent intermediate units. Each intermediate unit is thus held against lateral or horizontal displacement, and also against vertical or transverse displacement. The assembled units thus form a flexible assembly, in which each unit can be turned through a substantial angle relative to the next adjacent unit, without releasing the connection which is provided by the interlocked lugs and flanges. The edges L of the face-walls 2 limit said relative turning movement of the units. Said edges L about the adjacent flanges, when the relative turning movement is at the predetermined maximum limit.

Assuming that each assembled wall of the handbag B is in a vertical plane, the assembled units in each said wall can turn horizontally inwardly or outwardly relative to each other, through predetermined maximum angles, without releasing the connection of the lugs and slotted flanges.

The units are also connected by means of bendable connecting members 21, which can be wires, or cords, or heavy yarns. Said connecting members can be made of any bendable or flexible material.

As shown in Fig. 2, each connecting member 21 has successive connecting legs 21a, which are equally inclined to a horizontal line.

The successive legs 21a are arranged in zig-zag relation.

At the junction between two successive legs 21a in an intermediate unit, each connecting member 21 is passed through a respective lug-slot and a respective associated flange-slot. Intermediate its ends, each leg 21 is passed through another respective lug-slot and also through its respective associated flange-slot. Each respective intermediate unit 1 is thus connected to each of the next adjacent four units. The connection which is provided by the members 21 is inoperative per se to provide an assembled mesh structure, since it is necessary to use the interlocking lugs and flanges.

By using said interlocking lugs and flanges, I can use cylindrical members 21 of small diameter. Said members 21 can be sufficiently stiff and sufficient in diameter, to fit tightly in the respective pairs of registering lug-slots and flange-slots, so that it is impossible to release the lugs from the flanges when the members 21 are in position, unless excessive stress is imposed.

The members 21 can be substantially non-elastic or they can be more or less elastic. The ordinary cord or thick sewing thread has some elasticity, sufficient for the purposes of my invention. Said members 21 are maintained under tension.

In this embodiment, the members 21 form a single series. Each member 21 is associated with two horizontal rows of units.

The corner unit 15 which is shown in Fig. 10, has a single lug 6, a single slotted flange 3, and additional perforated flanges F. These flanges F are identical with flanges 3 and 5, save that flanges F have perforations 12, instead of being slotted. The lugs are identical in all the units.

10 The corner unit 18 which is shown in Fig. 5, has the two slotted lugs 4 and 6, and two flanges F.

15 The corner unit 14 which is shown in Fig. 12, has two slotted flanges 3 and 5, and two unslootted and perforated flanges F.

20 The corner unit 15 which is shown in Fig. 10, has a single slotted lug 6, a single slotted flange 3, and two flanges F.

25 The corner unit 17 which is shown in Fig. 8, has a single slotted lug 4, a single slotted flange 5, and two flanges F.

20 Each top unit 16 of the top edge-row 22, as shown in Fig. 11, has a top flange F, slotted flanges 3 and 5, and a single slotted lug 6.

25 Each bottom unit 19 of the bottom edge-row 23, as shown in Fig. 7, has slotted lugs 4 and 6, and a slotted flange 5, and a single flange F.

30 Each unit 10 of the left vertical edge-row 24, as shown in Fig. 4, has slotted lugs 4 and 6, a single slotted flange 3, and a single flange F.

35 Each unit 20 of the right vertical edge-row 25, as shown in Fig. 9, has a single slotted lug 4, two slotted flanges 3 and 5, and a single flange F.

The respective flanges F are identical. Each flange F is identical with a slotted flange 3 or 5, save that flanges F are unslootted, and each flange F has one or more holes.

In each unit, the free edges of its flanges and of its lug or lugs, are located in a square outline, said square outline being identical.

The units are of equal depth. Hence, if the outer planar faces of their face-walls 2 are supported on the same horizontal planar support, the free edges of the lugs and flanges of said units will be located in a common horizontal plane.

In making a hand-bag structure, each assembly of units is fixed to a backing Fa. This backing Fa may be made of fabric or any material. The backing Fa may be rigid or resilient or freely bendable.

The finished article is not limited to any method of assembly.

55 The preferred method is to assemble the units in interlocking relation upon a common horizontal planar support, so that the outer planar faces of the face-walls 2 rest upon said support.

Each edge of the assembly has a continuous succession of flanges F.

As an illustration, Fig. 13 shows six horizontal rows of units, each row having nine units.

Fig. 14 shows how said units are connected by ten connecting members 21c, 21d, 21e, 21f, 21g, 21h, 21-l, 21m, 21n, and 21p. Each said connecting member passes through a hole 12 in a respective vertical flange F. Each vertical flange F has three vertical holes. When two connecting members 21 pass through a single vertical flange F, said connecting members preferably pass through the top and bottom holes 12 of the respective vertical flange F. In Fig. 14, the outlines of the units are shown in broken lines. The zig-zag legs of said connecting members are arranged in respective assembled groups,

each group being square shaped, and connecting four adjacent units.

Each unit 16 and 18 has two zig-zag legs located therein. Each unit 1 has four zig-zag legs located therein.

Each corner unit 15, 14, 18 and 17 also has two zig-zag legs located therein.

The free ends of said connecting members are fixed to the respective backing Fa by adhesive or in any other manner. The free ends of said connecting members can be passed through said respective backings Fa, and said loops can be locked in position by using any conventional lock stitch.

The top and bottom flanges F of the top and bottom rows of units are fixed in position by loops 21b, which can be made of any flexible material, and which pass through or are otherwise fixed to the respective backings. Each middle hole 12 of each vertical flange F can be provided with a similar loop.

Fig. 2 shows that a pair of connecting legs pass through each horizontal lug-slot and its associated flange-slot in crossed overlapping relation. Fig. 2 also shows that the legs are vertically separated from each other, in each vertical lug slot and its associated flange slot. Due to the tension on the legs, the legs are separated from each other in each vertical lug-slot, the respective angular junctions between the legs being located respectively at the tops and bottoms of said lug slots.

The tension on the legs hold their portions which pass through the horizontal lug-slots, forced against the respective ends of said horizontal lug-slots.

In the embodiment illustrated herein, the lugs are shaped so as to provide a continuous mesh structure, in which the edges of the units abut each other.

The invention is not limited to any specific shape for the bodies of the units, or to any of the details disclosed herein, in order to show a single embodiment of my invention.

The members 4, 6, 8, and 5 of each unit 1, are generically designated as the flange-portion of the unit. Said flange-portion has a pair of slots 8 and 8a, and a pair of lugs 4 and 6, which have respective lug slots. Each flange-slot is aligned with and it is wider than a respective lug-slot. The flange-slots are wider than the lugs.

The connecting members may be vertically disposed, instead of being horizontally disposed.

The invention is not limited to a wall in which each and every part consists of the units described herein. Hence, when I refer to a series of units I may refer to the construction of the entire mesh structure, or to only a part of said mesh structure.

I claim:

1. A structural unit which has a flange-portion, said flange-portion having a pair of flange-slots and a pair of lugs, each said lug having a lug-slot, each flange-slot being aligned with and being wider than a respective lug-slot, the flange-slots being wider than said lugs.

2. A mesh structure which comprises a series of units which are arranged in longitudinally aligned and in laterally aligned relation so that each unit is a member of a longitudinal row of units and of a lateral row of units, said units

having flanges which have flange-slots, said units also having lugs which are located in said flange-slots to interlock said units, said lugs having lug-slots, connecting members passing through said flange-slots and through said lug-slots and preventing the withdrawal of said lugs from said flange-slots,

3. A mesh structure which comprises a series of units, said units having flanges, said flanges having flange-slots, said units having lugs, said lugs having lug-slots, respective lugs being located in respective associated flange-slots to interlock said units, each lug-slot being in registration with the respective flange-slot with which it is associated, bendable connecting members, each said connecting member comprising a succession of connecting legs which are disposed in zig-zag formation, each said leg being located intermediate the ends of said leg in a lug-slot and in a respective registering flange-slot, the junctions between successive legs being located in a lug-slot and in a respective registering flange-slot, said connecting members preventing the withdrawal of said lugs from said flange-slots.

4. A mesh structure which comprises a series of units, said units having flanges, said flanges having flange-slots, said units having lugs, said lugs having lug-slots, respective lugs being located in respective associated flange-slots to interlock the said units, each lug-slot being in registration with the respective flange-slot with which it is associated, bendable connecting members, each said connecting member comprising a succession of connecting legs which are disposed in zig-zag formation, each said leg being located intermediate the ends of said leg in a lug-slot and in a respective registering flange-slot, the junctions between successive legs being located in a lug-slot and in a respective registering flange-slot, said connecting members preventing the withdrawal of said lugs from said flange-slots, said connecting members having end-portions which extend through the walls of the edge-units of said series.

5. A mesh structure which comprises a series of units, said units having flanges, said flanges having flange-slots, said units having lugs, said lugs having lug-slots, respective lugs being located in respective associated flange-slots to interlock said units, each lug-slot being in registration with the respective flange-slot with which it is associated, bendable connecting members, each said connecting member comprising a succession of connecting legs which are disposed in zig-zag formation, each said leg being located intermediate the ends of said leg in a lug-slot and in a respective registering flange-slot, the junctions between successive legs being located in a lug-slot and in a respective registering flange-slot, said connecting members preventing the withdrawal of said lugs from said flange-slots, said mesh structure having a backing associated therewith, said connecting members having end-portions which extend through the flanges of the edge-units of said series, said end-portions being fixed to said backing, additional connecting members which fix the flanges of said edge-units to said backing, said edge-units being held against movement in any direction relative to said backing.

EDMUND W. BAGGOTT.
